UNITED STATES PATENT OFFICE.

JAMES F. LOCKWOOD, OF PHILADELPHIA, PENNSYLVANIA.

DESIGN FOR A SOAP-DISH.

SPECIFICATION forming part of Design No. 14,495, dated December 18, 1881.

Application filed October 29, 1883. Term of patent 3½ years.

To all whom it may concern:

Be it known that I, JAMES F. LOCKWOOD, a citizen of the United States, and a resident of Philadelphia, Pennsylvania, have invented 5 a new and original Design for a Soap-Dish, of which the following is a specification.

My design is fully shown in the accompanying drawing, and comprises the tray A, rim or flange B, and upturned projection D 10 at one side. The tray is made in imitation of a shell, and has around the edge a bead, a, which is continued around the edge of the projection D. The rim B also has beads b and d;

but the beads are not an essential part of the design.

I claim—

The design for a soap-dish, said design comprising the shell-like tray A, rim B, and upturned projection D, as shown and described.

In testimony whereof I have signed my name 20 to this specification in the presence of two subscribing witnesses.

JAMES F. LOCKWOOD.
